UNITED STATES PATENT OFFICE

114,197

DESIGN FOR A BATH BRUSH OR THE LIKE

Peter Müller-Munk, Pittsburgh, Pa., assignor to Pro-phy-lac-tic Brush Company, Northampton,
Mass., a corporation of Delaware

Application February 2, 1939, Serial No. 82,742

Term of patent 7 years

To all whom it may concern:

Be it known that I, Peter Müller-Munk, a citizen of the United States of America and a resident of Pittsburgh, in the county of Allegheny, State of Pennsylvania, have invented a new, original, and ornamental Design for Bath Brushes or the like, of which the following is a specification, reference being had to the accompanying drawing, forming part thereof.

In the drawing:

Fig. 1 is a top or back plan view, and
Fig. 2 is a side view of a bath brush showing my new design.

Figs. 3 and 4 are sections taken substantially on the lines 3—3 and 4—4, respectively, Fig. 1.

I claim:

The ornamental design for a bath brush or the like, substantially as shown.

PETER MÜLLER-MUNK.
